OF ST. LOUIS, MISSOURI, A CORPORATION OF MISSOURI.

CAST-METAL AXLE FOR VEHICLES.

No. 922,684.

Specification of Letters Patent.

Patented May 25, 1909.

Application filed March 23, 1908. Serial No. 422,302.

To all whom it may concern:

Be it known that I, CHARLES G. ETTE, a citizen of the United States, residing at St. Louis, Missouri, have invented a certain new and useful Improvement in Cast-Metal Axles for Vehicles, of which the following is a full, clear, and exact description, such as will enable others skilled in the art to which it appertains to make and use the same, reference being had to the accompanying drawings, forming part of this specification, in which—

Figure 1 is a perspective view of my improved axle, the axle being arranged in the reverse position to that which it occupies when in operative position on a vehicle; Fig. 2 is a top plan view of a portion of the axle; Fig. 3 is a vertical longitudinal sectional view of Fig. 2; Fig. 4 is a cross sectional view taken on the line 4—4 of Fig. 2 looking in the direction of the arrow; Fig. 5 is a cross sectional view taken on the line 5—5 of Fig. 2; Fig. 6 is a cross sectional view taken on the line 6—6 of Fig. 3; Fig. 7 is a detail top plan view of the outer end of one of the tapered end portions of the axle; and Fig. 8 is a perspective view of the key that locks the wheel nut in position.

This invention relates to axles for vehicles. The main object of my invention is to provide a cast metal axle that is strong and which can be produced at a low cost, said axle being preferably made of malleable iron.

Another object of my invention is to provide a cast metal axle provided with detachable skeins having integral screw-threaded extensions which receive the nuts that hold the wheels on the skeins. And still another object of my invention is to provide an axle having detachable cast metal skeins which are thickened on their lower sides to compensate for wear, and improved means for connecting said skeins to the axle.

Other desirable features of my invention will be hereinafter pointed out.

Referring to the drawings which illustrate the preferred form of my invention, A designates the central portion of my cast metal axle which is preferably of inverted channel shape in cross section. The central web 1 of the channel forms the upper side of the axle and said web is provided on its inner face with integral depending bosses 2 having openings for receiving the fastening devices which connect the underframe of the vehicle

to the axle. On the upper side of said web 1 are integral ribs 3 that embrace the under-frame members. The central portion of the axle is provided with cross webs 4 integrally connected to the bosses 2, and a longitudinally extending rib or flange 5 which is integrally connected to the bosses 2 and to the inside face of the central web 1. Adjacent to the ends of the central portion of the axle are horizontally disposed webs 6 that are integrally connected to the lower edges of the side legs or flanges of the channel, as shown in Fig. 1. The end portions 7 of the axle are tapered and are of approximately circular shape in cross section, said end portions 7 being integrally connected to the central channel-shaped portion of the axle. Preferably, the rib or flange 5 on the inside of the axle is continued through said end portions 7, as shown in Fig. 3, for the purpose of strengthening same. The lower sides of the end portions 7 are flattened at 7^a, as shown in Fig. 1, and on the inside faces of these flattened portions are integral strengthening ribs 8, as shown in Fig. 3.

As shown in the drawings, all portions of the axle are of about the same thickness so that the heat can penetrate into the metal thoroughly during the annealing operation and thus prevent the metal from cracking when it cools off.

Shoulders 9 are formed adjacent to the inner ends of the end portions 7 to form abutments for the inner ends of cast metal skeins 10 that are mounted on said end portions. The inside faces of said skeins conform to the cross sectional shape of the end portions 7 and consequently said skeins cannot rotate as they have flat faces which bear upon flat faces 7^a on the end portions. Each of the skeins 10 is provided with an integral extension 11 provided with external screw-threads for receiving the nut which holds the wheel on the skein, as shown in broken lines in Fig. 2 so that in case the portion of the axle that projects beyond the wheel should be broken off it will only be necessary to substitute a new skein and not an entire new axle. By providing the skein with a flat face for engaging the flat face on the end portion 7 of the axle I produce a thickened portion on the underneath side of the skein which compensates for the excessive wear which this portion of the skein receives and thus enables the skein to be used for a long time.

The outer ends of the tapered portions 7 of the axle are closed and each of said portions is provided with a slot 12 for receiving a T-shaped key 13, the shank of which extends through the extension 11 on the skein and projects beyond the nut mounted on said extension. The skein holds said key in position and a cotter pin 14 passes through the shank of said key so as to lock the wheel 10 nut in position. Each of the skeins 10 is locked to the tapered portion 7 of the axle on which it is mounted by means of a bolt 15 that extends transversely through said parts, and the skein is provided with an integral 15 lug or rib 16 which engages the head of the bolt to prevent it from turning. A washer 17 is interposed between the skein and the nut 18 on said bolt and said washer is provided with a lip that can be bent up to engage 20 the nut and thus lock it on the bolt.

Having thus described my invention, what I claim as new and desire to secure by Letters Patent is:

1. A cast metal axle having end portions 25 provided with flat faces, removable skeins mounted on said end portions and provided with coöperating flat faces which prevent said skeins from rotating, said skeins having end walls that butt against the extreme ends 30 of the axle and hollow screw-threaded extensions that project beyond the ends of the axle, and nut-retaining devices arranged in said hollow extensions; substantially as described.

35 2. A cast metal axle having a central portion of inverted channel shape in cross section and integral end portions, an integral rib or flange extending longitudinally through said central portion and end portions, and integral cross webs in said central portion; substantially as described.

3. A cast metal axle having a central portion of inverted channel shape in cross section and integral tapered end portions, skeins 45 detachably connected to said end portions and provided with hollow screw-threaded extensions for receiving wheel nuts, said exten-

sions extending beyond the extreme ends of the tapered end portions of the axle, removable keys carried by the end portions of the 50 axle and extending through the hollow extensions of the skeins, and devices on said keys for locking the nuts that are mounted on said hollow extensions; substantially as described.

4. A cast metal axle having hollow end portions provided with end walls in which slots are formed, removable keys projecting through said slots and having heads that engage the inside faces of said end walls, 60 skeins connected to the axle and provided with screw-threaded extensions through which said keys extend, and locking devices carried by said keys; substantially as described.

5. A cast metal axle provided with tapered end portions that are flattened on their lower sides, strengthening ribs on the inside faces of said flattened portions, and removable skeins mounted on said end portions and provided with flat faces which engage said flattened portions and thus prevent the skeins 70 from turning; substantially as described.

6. A cast metal axle having a central portion which is of inverted channel shape in 75 cross section, integral ribs on the upper side of the axle to receive the underframe members of a vehicle, perforated bosses depending from the central web of the channel, longitudinally extending ribs and cross webs for 80 strengthening said bosses, horizontally disposed webs connecting the lower edges of the legs of the channel together, and tapered end portions formed integral with the inverted channel-shaped portion; substantially as 85 described.

In testimony whereof I hereunto affix my signature in the presence of two witnesses, this twentieth day of March 1908.

CHARLES G. ETTE.
